UNITED STATES PATENT OFFICE.

ALCIDE HECTOR MAÎTRE AND VICTOR HENRI GASTON MARTIN, OF ROUEN, FRANCE.

DAMPER FOR CONTACT-BREAKER DEVICES FOR ELECTROMAGNETIC VIBRATING MEMBERS.

Application filed April 14, 1922. Serial No. 552,503.

To all whom it may concern:

Be it known that we, ALCIDE HECTOR MAÎTRE and VICTOR HENRI GASTON MARTIN, both citizens of the French Republic, and both residents of 92 Rue de la République, Rouen, Department of Seine Inférieure, France, have invented new and useful Improvements in Dampers for Contact-Breaker Devices for Electromagnetic Vibrating Members, of which the following is a specification.

The present invention has for an object to damp rapidly all oscillatory motion of a movable member; it relates more especially to contact-breaker devices for electro-magnetic vibrating members, and in particular to the arrangements described in the United States Patents No. 1,106,230 of August 4, 1914 and No. 1,188,295 of June 20, 1916.

These last arrangements are characterized particularly by the fact that the contact member, intended to close the electric circuit by its contact with the vibrating body (gong, plate, string or other element), is carried by a movable arm mounted upon a pivot and adapted to perform oscillations of small amplitude.

Experience has shown that in order to obtain a pure note, and to allow this note to be established rapidly, it is of advantage, especially in the case of vibrating piano-strings, to reduce as far as possible the amplitude of the oscillations of the movable contact member.

The present invention relates to a device allowing this result to be attained and is based upon the principle of braking or damping the oscillations of the movable contact member by means arranged in such a way as to produce no oscillatory reaction in the direction of the displacement of the said movable contact member.

The annexed drawings represent by way of example various forms of construction in accordance with the invention:

Fig. 1 is an elevation of one form of the invention applied to a device for vibrating a piano string;

Fig. 2 is a horizontal section upon line 2—2 of Fig. 1;

Fig. 3 is a vertical section upon line 3—3 of Fig. 1;

Fig. 4 is a perspective view of a mechanism for renewing the points of contact in the construction shown in Figs. 1 to 3;

Fig. 5 is a front elevation partly broken away and partly in section showing the application of the oscillation brake system of Figs. 1 to 3 to a device for vibrating a gong; and

Fig. 6 is a side elevation corresponding to Fig. 5.

In the form of construction illustrated in Figures 1, 2 and 3, *a* is a piano string, *b* the electromagnet which vibrates it, and *c* a rocking arm carrying the movable contact piece *c'*. The movable arm *c* is mounted upon the pivot *c*² supported by a wooden block *l* integral with another wooden block *m*, the pivot *c*² terminating in two cone centers upon which are journaled the two legs of the stirrup-shaped oscillating plate *c*. There is a lead weight *c*³ offset in relation to the pivotal axis *c*² of the plate and serving to balance the oscillating plate *c* as well as to provide means for riveting together the two legs of the stirrup-shaped oscillating plate. A steel plate *c*⁴ in the shape of a cylinder divided along a generatrix, is arranged to form a spring, its free ends being engaged slidably in a groove formed at the lower end of the oscillating plate *c*; the movable contact piece *c'* consists of a bundle of annealed silver wires, clamped in the cylindrical plate spring *c*⁴ and therefore, adjustable in position in the groove at the lower end of the oscillating plate *c*. The stirrup-forming legs of this oscillating plate *c* pivot freely with slight play upon the conical points of the spindle *c*². To the movable arm *c* there is suspended, by a metal wire *j*¹ clamped beneath a screw *j*², a piston *j* plunged in a more or less viscous liquid *k*, contained in a vessel *k*⁶, supported by the block *m*. This vessel *k*⁶ is provided above the level of the liquid *k* with an orifice having a tubular neck *k*⁷ to prevent the liquid from overflowing, either as a result of expansion or because of the apparatus being tilted. This liquid can be rendered immune from oxidation by covering it with another liquid of lighter density not subject to oxidation, such as watchmaker's oil.

The vessel *k*⁶ supports by means of the plate *k*⁸ an electromagnet *b*¹ connected in series, in the energizing circuit of the main electromagnet *b*, exerting its attractional force upon the piano-wire or string *a*. The stationary contact *a*¹ is mounted upon a metal wire *a*² hooked at one end to the string *a* and at the

other end to the member a^3 . As a result of the method of mounting the electromagnet b^1 , the attraction of the armature e carried by the movable arm c , by the electromagnet b^1 , that is to say the break of contact at c^1, a^1 , takes place in synchronism with the variations of the energizing current of the main electromagnet b .

The two wooden blocks l and m are together pivoted at n upon a third wooden block o , firmly secured by a bolt q to a metal angle-bracket p , itself rigidly fixed to the body of the instrument.

The working of the device is as follows: The oscillating plate c is balanced by the eccentric weight c^3 in such a way that in the absence of current passing in the energizing circuit of the electromagnets b b^1 , the movable contact piece c^1 presses lightly upon the contact a^1 . When the plate c oscillates under the influence of the electromagnet b^1 and the weights acting upon the movable arm, the piston j moves in the body of viscous liquid k , so that any motion of the oscillating plate c is simply braked or slowed down without being prevented and without being followed by an opposite reactional movement, the displacements of the piston compelling the liquid to circulate through the restricted spaces which separate the piston j from the walls of the containing vessel. Under these conditions a considerable resistance is offered by the liquid to rapid movement of the piston and therefore of the oscillating plate c .

The position of the armature e in relation to the electromagnet b^1 can be adjusted by means of a square-headed screw a^4 , engaged in the wooden block m and abutting against the part o under the action of an opposing spring a^5 ; the armature e can thus be maintained constantly at the same distance from the electromagnet b^1 even if a slight wear of the contacts c^1, a^1 should be produced after several years of operation.

In order to effect the replacement of the metal wires a^2 carrying the contact pieces a^1 , the vessel k^6 is raised so that the wooden block l pivots around its axis n , compressing the spring a^6 between the blocks m and o ; the plate c under the contact c^1 thereupon releases the contact piece a^1 allowing ready access to the latter.

It has been found advantageous to constantly renew the points of contact between the surfaces c^1, a^1 and to cause continual rubbing of these parts against one another. For this purpose the metal angle-bracket p shown in Figure 1 supporting the device is itself supported as shown in Figure 4 by eccentric rods p^1 , the driving eccentrics p^2 of which are secured upon a horizontal shaft p^3 . This shaft revoluble in bearings p^4 carries at one end a pulley p^5 driven by the shade controlling means, i. e. by means of the belt p^6 by the mechanism (not shown) for

producing the gradations of forte, piano and pianissimo.

This mechanism therefore produces by the rotation imparted to the shaft p^3 an upward and downward movement of the angle-section bar p , and causes rubbing of each of the contact pieces c^1 upon the corresponding contact a^1 . The angle-bar p carries slides p^7 each having a slot in which there works a screw p^8 fixed to a vertical guiding surface p^9 so as to ensure a truly vertical motion of the bar p .

Figures 5 and 6 represent the application of the damping device with piston submerged in a viscous liquid, to the case of the vibration of a gong a , operated by the electro-magnet b ; the plate c integral with the pivot c^2 and carrying the movable contact c^1 comprises an arm c^5 directed at right angles in relation to the plate c and connected by a metal wire j^1 to a small piston j submerged in a viscous liquid, for example castor oil, in the tubular vessel k^6 . The latter is supported by means of clips or collars d^1 directly upon a bracket d^2 integral with the support d in which the contact device is pivoted.

When the plate c oscillates under the influence of the electromagnet b , its oscillations are rapidly damped by the resistance opposed by the viscous liquid k to the displacements of the plunger j .

The tube k^6 being of very small diameter there is no need to provide, as in the example illustrated in Figures 1 to 3, a constricted neck to prevent the liquid from overflowing; the liquid is maintained in the tube by capillarity in spite of possible tilting or expansion.

It will be understood that the forms of construction described and shown in the drawings have been given merely by way of examples, and that they may receive a large number of detail modifications without departing from the scope of the claims, for example as regards the shape of the movable contact piece and its method of excitation; the electromagnets b^1 may be connected in parallel or in series with the main electromagnet b and they may tend to break the contact at c^1, a^1 when these parts are in contact, or on the contrary they may tend to bring the contacts together when they are separated by an opposing spring, weight or other force.

What we claim is:

1. In an electric circuit, an electro-magnetically vibrated member, a contact vibrating in unison therewith, a second contact cooperating with the first mentioned contact to complete the operating electro-magnetic circuit, a movable arm carrying said second contact, electrical means operating in said circuit and adapted to vibrate the said second contact and to produce forced breaks at the beginning of the vibration, a fixed

vessel containing a viscous liquid, a plunger connected to the movable arm and immersed in said viscous liquid, said plunger being of sectional area slightly less than that of the liquid-containing vessel, for the purpose described.

2. In a music instrument, an electric circuit, an electro-magnetically vibrated string, a contact vibrating in unison therewith, a second contact cooperating with the first mentioned contact to complete the operating electro-magnetic circuit, a movable arm carrying said second contact, electrical means operating in said circuit and adapted to 15 vibrate the second contact and to produce forced breaks at the beginning of the vibration of the string, a fixed vessel containing a viscous liquid, a plunger connected to the movable arm and immersed in said viscous liquid, said plunger being of sectional area slightly less than that of the liquid-containing vessel, for the purpose described.

3. In an electric circuit, an electro-magnetically vibrated member, a contact vibrating in unison therewith, a second contact cooperating with the first mentioned contact to complete the operating electro-magnetic circuit, a frame member, a rocker arm pivotally mounted on said frame member and carrying 25 said second contact, means electromagnetically operating in said circuit and adapted to vibrate said second contact and to produce forced breaks at the beginning of the vibration, said means comprising an electromagnet carried by the frame member and an armature carried by the rocker arm, a fixed vessel containing a viscous liquid, plunger connected to the movable arm and immersed in said viscous liquid, said plunger being of

sectional area slightly less than that of the liquid-containing vessel, for the purpose described.

4. In an arrangement as claimed in claim 3, the provision of means for adjusting the armature, carried by the rocking arm, in relation to the electromagnet vibrating the movable contact.

5. In an arrangement as claimed in claim 3, the provision of means for ensuring a continuous relative displacement of both contacts and a continuous friction of said contacts the one against the other, for the purpose described.

6. In an arrangement as claimed in claim 3, the provision of a bar carrying the frame member, supporting the electromagnetically vibrated second contact, and of means for reciprocating said bar, for the purpose described.

7. In an arrangement as claimed in claim 3, applied to a piano, a bar carrying the frame members of all of the electro-magnetically vibrated movable second contacts, shade controlling means for the piano, and means actuated by said shade controlling means adapted to reciprocate said bar and ensure a continuous relative displacement of both contacts of each pair and a continuous friction of one contact against the other of the said pair, for the purpose described.

In testimony whereof they have signed their names to this specification.
